UNITED STATES PATENT OFFICE.

ARTHUR McDougall DUCKHAM, OF ASHTEAD, ENGLAND.

DISCHARGING VERTICAL RETORTS.

1,169,017.

Specification of Letters Patent. Patented Jan. 18, 1916.

Application filed July 28, 1915. Serial No. 42,378.

To all whom it may concern:

Be it known that I, ARTHUR McDougall DUCKHAM, a subject of the King of Great Britain, residing in Ashtead, England, have invented certain new and useful Improvements in Discharging Vertical Retorts, of which the following is a specification.

My invention relates to a method of discharging through a water seal, a vertical retort wherein coal or the like is continuously carbonized. The method consists in imparting a reciprocating or oscillatory movement to a water trough which forms the seal and wholly or partially supports the charge of the retort, and in completely or partially preventing the material in the trough from sharing this movement in one direction so that at each movement some 10 of the material leaves the trough and fresh material descends into the trough. There are several manners in which this method may be applied. For instance, the lower end of the retort or an extension thereof 15 may extend into a water trough mounted to rock on a suitable axis, there being sufficient room between the end of the retort or extension and the bottom of the trough for passage of the carbonized material. Be- 20neath the end of the retort or extension there is a stationary plate or the like acting as a scraper in relation to the bottom of the trough. When the trough is oscillated by a suitable mechanism the carbonized ma- 25 terial is carried with it by the movement in one direction and a free space is left between the material and the scraper into which some of the charge in the retort de- 30 scends, while during the movement in the other direction the scraper prevents the ma- 35 terial from moving with the trough so that some of the material falls over the edge of the latter. By placing the scraper on a line bisecting or substantially bisecting the dis- 40 charge opening of the retort or extension, the movement of the trough in each direc- 45 tion becomes effective in discharging the carbonized material. When the scraper is flush with one side of the retort, in which 50 case it may be an extension of the side or the longer side of an obliquely cut discharge opening, the movement of the trough in one direction only is effective for discharg- 55 ing from the trough. A rectilinear recipro-

cating movement may be substituted for the oscillatory movement of the trough.

In the accompanying drawing Figure 1 is a vertical section through a water trough into which the lower end of a retort ex- 60 tends; Fig. 2 is a similar view of a modified construction.

In Fig. 1 the trough A is supported so as to oscillate about the hinge B. D is the lower end of the retort, which extends below the water seal C. E is a scraper se- 65 cured to the retort. As the trough is caused to swing to the left as shown in full lines, the carbonized material is discharged over the right edge, and when the trough is swung to the right as shown in dotted lines, 70 the material is discharged over the left edge of the trough. Also, at each oscillation some of the charge falls into the trough.

In Fig. 2 the trough A₁ is adapted to re- 75 ceive a reciprocating motion on the rollers F, instead of an oscillatory motion, and in this example one side G of the retort is extended to act as a scraper. It is obvious that when the trough is moved to the left, some of the carbonized material is dis- 80 charged over the right edge of the trough, and that when the trough is moved to the right some of the charge falls from the re- tort into the trough.

Having thus described the nature of the 85 said invention and the best means I know of carrying the same into practical effect, I claim:—

1. Means for discharging carbonized ma- 90 terial from a vertical retort, comprising in combination a trough forming a water seal for the retort, means for imparting a to- and-fro movement to the said trough, and means for preventing this movement from being fully imparted to the material in the 95 trough.

2. Means for discharging carbonized ma- 100 terial from a vertical retort, comprising in combination a trough forming a water seal for the retort, means for imparting a to- and-fro movement to the said trough and a stationary scraper in the trough adapted to prevent the movement of the trough from being fully imparted to the material therein.

3. Means for discharging carbonized ma- 105 terial from a vertical retort, comprising in combination a trough forming a water seal for the retort, means for imparting a to-

and-fro movement to the said trough and a stationary scraper secured to the vertical retort and adapted to prevent the movement of the trough from being fully impacted to the material therein.

4. Means for discharging carbonized material from a vertical retort, comprising in combination a trough forming a water seal for the retort, means for imparting a to-and-fro movement to the said trough and a stationary scraper in the trough, substantially bisecting the discharge opening of the retort whereby the movement of the trough in each direction becomes effective in discharging the carbonized material.

5. Means for discharging carbonized material from a vertical retort, comprising in combination a trough pivoted about a horizontal axis and forming a water seal for the retort, means for imparting an oscillatory motion to the trough about the said axis

and means for preventing this movement from being fully imparted to the material in the trough.

6. Means for discharging carbonized material from a vertical retort, comprising in combination a trough pivoted about a horizontal axis and forming a water seal for the retort, means for imparting an oscillatory motion to the trough about the said axis, and a stationary scraper, substantially bisecting the discharge opening of the retort, whereby the movement of the trough in each direction becomes effective in discharging the carbonized material.

In testimony whereof I have signed my name to this specification in the presence of two subscribing witnesses.

ARTHUR McDougall DUCKHAM.
